United States Patent Office.

ELIAS SHOPBELL, OF ASHLAND, OHIO.

Letters Patent No. 101,528, dated April 5, 1870.

IMPROVEMENT IN PATTERNS FOR SHOES.

The Schedule referred to in these Letters Patent and making part of the same.

To all whom it may concern:

Be it known that I, ELIAS SHOPBELL, of Ashland, in the county of Ashland and State of Ohio, have invented certain new and useful Improvements in Shoe-Patterns; and I do hereby declare that the following is a full and complete description of the same, reference being had to the accompanying drawings making a part of this specification, in which—

Figure 1 is a view of a shoe-back pattern.

Figure 2, a view of a shoe-front pattern.

Like letters of reference refer to like parts in the several views.

The nature of this invention relates to a pattern for cutting out shoe-backs and fronts, the arrangement of which being such that said pattern can be adjusted for cutting all sizes of men's and boys' wear, thereby dispensing with a number or series of patterns of different sizes, as now usually employed.

Fig. 1 represents a pattern for shoe-backs, and which consists of seven plates, viz:

A B, which form the lower part or heel of the back, and may be considered as the primary plates, whereby the others are moved conjointly therewith.

The plates C D E F and G form the upper part of the back and lapet for the tie or lacings.

It will be observed that plates B C and D are duplicates of the plates A F and G, and that they are all connected to the central plate E, and the plates A B by the studs *a*, said studs being fixed in the under-lap of the plates at certain determined points, and projected through the over-lap of the plates in slots *b*. The peculiar direction or angle given to each and all the slots, and the respective relation that they hold to each other, and more especially to the slots *i*, through which the thumb-screw passes, are such that, upon the lateral extension of the primary plates A B, as indicated by the dotted lines *c*, the supplementary plates C D E F and G are extended at the same time and in proportional degree, as indicated by the dotted lines *e*.

The simultaneous movement of the plates occasioned by the determined angle or direction that the slots bear to each other causes an equal enlargement or contraction of the several plates; hence, to cut a back of a shoe to a certain size, a scale of sizes, H, on the plate B, and seen through the slot, will determine the size sought, from one to ten, the range of sizes for men's and boys' wear.

The front of the shoe is also cut from a pattern relatively corresponding to the back pattern above described, and which is represented in fig. 2.

This pattern is composed of three plates, A B and

C, the general outlines of which are those proper for the vamp or front of the shoe, as that above described is that for the back.

The two plates A B move laterally, whereas the plate C moves upwardly, or at a right angle to the movement of the plates A B. The movement of the plate C is governed by the direction given to the slots *a*, in which the studs *b* move and connect the plates to each other.

By this simultaneous and equal movement of the plates on their extension or contraction is obtained the different sizes for the shoes. A scale of sizes corresponding to that on the back pattern is inscribed on the front, hence, the two patterns have the same proportional extension and contraction, ranging from one up to ten, for men's and boys' wear.

I am aware that shoe-patterns, consisting of a number of plates, which are expanded and contracted by a system of studs moving in slots of certain directions, have been used. This I do not claim, broadly; but that which distinguishes my invention from others is the construction of one pattern for shoes, whereby all the different sizes which are worn by men and boys can be cut, thereby dispensing with the use of several patterns, as is required when made in the ordinary way.

Patterns, as usually constructed, have a single movable back-plate, to which the supplementary movable plates are attached, and therewith relatively operated. Such patterns can be used for cutting only a limited number of sizes; hence, to cut the entire range of men's and boys' sizes a number of patterns are required, whereas my pattern is so constructed that one only is necessary for that purpose, thereby dispensing with the trouble of using several different patterns, and saving the expense of the same.

What I claim as my invention, and desire to secure by Letters Patent, is—

1. A pattern for cutting backs of shoes, constructed of plates A B, plates C D E F and G, with their several respective slots *b*, all arranged in relation to each other, and combined to operate in the manner substantially as described and for the purpose specified.

2. A pattern for cutting fronts of shoes, constructed with plates A B, plate C, and their respective slots *a*, when arranged in relation to each other, and combined to operate in the manner substantially as described and for the purpose set forth.

E. SHOPBELL.
